United States Patent Office

Des. 197,712
Patented Mar. 17, 1964

197,712

CHAIR

Howard Edwin Fischer, Jr., 3540 Brotherton Road,
Cincinnati, Ohio

Filed Jan. 25, 1963, Ser. No. 73,306

Term of patent 7 years

(Cl. D15—1)

Fig. 1

I claim:

The ornamental design for a chair, as shown.
